UNITED STATES PATENT OFFICE.

HERBERT O. ROSS, OF ST. LOUIS, MISSOURI.

FILE OR RACK FOR PAPERS, DOCUMENTS, MERCHANDISE, AND THE LIKE.

Application filed June 8, 1925. Serial No. 35,673.

This invention relates to a certain new and useful improvement in racks or files for papers, documents, merchandise and the like and has for its chief object the provision of a rack or file of the class stated comprising a plurality of simple and inexpensive compartment-forming co-operating sections or units adapted for convenient detachable connection the one with the other for varying both the capacity of respective compartments and the capacity of the complete file or rack.

And with the above and other objects in view, my present invention resides in the novel features of form, construction, arrangement, and combination of parts hereinafter described and pointed out in the claims.

In the accompanying drawing, Figure 1 is a plan view of a file or rack embodying my invention;

Figure 2 is an end view of the file or rack; and

Figure 3 is an enlarged perspective view of one of the units of the file or rack.

Referring now more in detail and by reference characters to the drawing, which illustrates a preferred embodiment of my invention, the file or rack comprises as a whole a plurality of compartment-forming sections or units each of which is formed preferably of a single piece or section of suitable material, such as sheet metal, of size and dimensions to include by bending a base-wall 1, a side wall 2, and a back or end wall 3. Preferably, as shown, base 1 and back wall 3 are each of oblong-rectangular configuration; side wall 2 however, for purposes shortly appearing, is preferably obliquely cut-away along its upper margin to be of greater height adjacent back wall 3 than at the front end of the unit. The unit is thus open not only at its top, but also both at one side opposite the one side wall 2 and at one end opposite the one end wall 3.

At or adjacent its opposite ends, base 1 is formed with a preferably square opening 4 and a rectangular slot 5, the end wall 3 being similarly formed adjacent its opposite side margins with a like opening 6 and slot 7.

For convenience now in describing the finished file, I shall designate the units as A, B, C, etc., and in assembling the file, a second unit B is disposed to fit within the confines of first unit A with its base 1 disposed flatwise at its margin upon the base

1 of the first unit A with the openings 4 of unit B registering with the slots 5 of unit A, with its side wall 2 presented towards the side wall 2 of the first unit, and with its back-wall 3 partly overlapping flatwise upon the free margin of the back-wall 3 of the first unit A, with the openings 6 of unit B registering with slots 7 of unit A. By means then of suitable fastening-members, such as preferably square-shank bolts adapted to receive wing-units 8, passed through the registering openings 6 and slots 7 of said units and by feet 9 having square threaded shanks projected through the registering square-openings 4 and slots 5, the units A and B are detachably secured together, the overlapping end walls of said units and the side wall 2 of the second unit B with the side wall 2 of unit A co-operating to form a compartment for the convenient reception of papers, documents, merchandise, and the like.

In such manner, and by additional units C, the size and capacity of the file may be adjustably enlarged to include any number of compartments so as to meet various requirements.

And to complete the final compartment, an end unit D of substantially the same form as units A, B, and C, but with its side wall 10 and end wall 11 reversed in direction relatively to its base, is likewise fitted upon and adjustably secured to the final unit C, as shown, the side wall 10 of unit D co-operating with the side wall 2 of the last unit C in completing the final compartment and the rack as so completed comprising a desired plurality of such open end compartments, the width or capacity of any of which being readily and selectively adjustable by reason of the base and end wall slots 5 and 7.

My new file or rack and its units or sections are of simple and inexpensive form and construction. The units or sections may be of any suitable size so that the complete rack may fit either within a desk or table-drawer or upon a table, counter, or desk, the reduced height of the side walls of the several units at the front end of the file affording easy gripping and removal of the contained papers or the like. The several sections may be readily attached together in file-completing co-operation, and the file as a whole is conveniently adjustable either to vary the capacity of the respective compartments or the number of such compartments.

And it is to be understood that changes in the form, construction, arrangement, and combination of the several parts of my new file or rack may be made and substituted for those herein shown and described without departing from the nature and principle of my invention.

Having thus described my invention, what I claim and desire to secure by Letters Patent is:

1. In a rack, a plurality of complementary compartment-forming separable units, each unit including a base wall and a single end wall and single side wall upstanding from the base wall and each unit being open upon its opposite end and side, said units being adapted to fit telescopically together with the end and side walls of one unit superposed over the respective end and side walls of the next adjacent unit, and means for separably securing said units together in compartment-forming relation.

2. In a rack, a plurality of complementary compartment-forming separable units, each unit including a base wall and a single end wall and single side wall upstanding from the base wall and each unit being open upon its opposite end and side, said units being

adapted to fit telescopically together in adjustable relation with the end and side walls of one unit superposed over the respective end and side walls of the next adjacent unit, and means for separably securing said units adjustably together, contiguous units, when so secured together, forming an open-end compartment.

3. In a rack, a plurality of complementary compartment-forming separable units, each unit including a base wall and a single end wall and single side wall upstanding from the base wall and each unit being open upon its opposite end and side, said units being adapted to fit telescopically together in adjustable relation with the end and side walls of one unit superposed over the respective end and side walls of the next adjacent unit, and means comprising fastening members engaging the telescopically disposed walls of the units for separably securing said units together, contiguous units, when so secured together, providing open end compartments.

In testimony whereof, I have signed my name to this specification.

HERBERT O. ROSS.
